UNITED STATES PATENT OFFICE.

ARNO MEREEN, OF BERKELEY, CALIFORNIA.

EDGER.

1,422,463.

Specification of Letters Patent. Patented July 11, 1922.

Application filed October 12, 1920. Serial No. 416,350.

To all whom it may concern:

Be it known that I, ARNO MEREEN, a citizen of the United States of America, and resident of Berkeley, in the county of Alameda, in the State of California, have invented certain new and useful Improvements in Edgers, of which the following is a specification, reference being had to the accompanying drawings.

10 My invention relates to machines known in the art of lumber manufacture under the generic name of edgers, and has for its object the production of a new machine of that class embodying a band-saw for dividing boards transversely into strips of uniform width.

15 The name appropriated by me to my machine, and which is, in general terms, distinctive of it, is a horizontal band-saw edger.

20 A general object of my invention is to promote economy of time, material, and labor in the edging or ripping of lumber. Another object is to provide means for effecting substantial uniformity in the manufacture of edging material, whereby such material may be accurately standardized in respect to width, with large economy in practice.

25 30 A further object of my invention is to reduce the waste of stock, due to the cut of the saw, to a minimum. That this could be accomplished theoretically by the use of a thin band-saw was obvious, but practically it could not be done to economical advantage, because the cut of such a saw is limited to a length of cut within which the saw in its travel will clear itself without choking.

35 40 This difficulty, for one thing, is overcome by my invention and the capacity of the band-saw indefinitely amplified by providing a succession of separated feed-boxes which independently present their respective feed material to one saw, thereby affording a clearance to the saw between the boxes, which, by offering a clean section of the saw blade to the material in each separate feed-box, affords effectual insurance against choking of the saw blade in its work, irrespective, substantially, of the number of boxes which may be embodied in a machine.

45 50 Other advantages, the attainment of which is included within the objects of my invention, will be apparent to those skilled in the art.

55 What constitutes my invention will be

hereinafter specified in detail and succinctly set forth in the appended claims.

In the accompanying drawings, which are intended to afford, in effect, substantially 60 diagrammatic illustration of my invention,

Figure I is a vertical section on the line I—I of Figure II, looking in the direction indicated in the latter by arrows.

Figure II is a top plan view of my machine in complete form of embodiment.

Figure III is a section on the line III—III of Figure I, looking from right to left, as indicated by arrows.

Figure IV is a view on an enlarged scale 70 of a portion of the subject matter of Figure III, showing a piece of material in process of being ripped by my machine into strips of unequal widths, as indicated by the partially formed dividing kerf between 75 them.

Referring to the numerals on the drawings, 1 indicates a floor, table, or plate made of any suitable material, dimensions, weight and stiffness that may be preferred. Upon 80 said plate, as indicated in Figure I, I provide a pair of pillow blocks 2 and 3 that are in service rigidly secured to their supporting member 1, the pillow blocks being preferably disposed in pairs, as illustrated in 85 Figure II. The blocks 2 carry, in true parallel relationship to the plate 1, a rotative shaft 5. In like manner, the blocks 3 carry a shaft 6, corresponding to the shaft 5. Either of the shafts 5 or 6 may be a driving 90 shaft and the other a driven shaft. The shaft 5, being the driving shaft as shown in the drawings, is provided with a belt pulley 7 for the application of power in the usual way. To the shafts 5 and 6, respectively, are secured band-saw pulleys 8 and 9 which are mounted in true co-operative relationship one towards the other for the operative accommodation upon their respective peripheries of a band-saw 10. The band-saw is stretched taut upon the said pulleys which are preferably made relatively adjustable in any usual manner for the purpose of keeping the band-saw taut, at due tension upon it. The upper stretch 11 of the band-saw is made the working portion of the saw. The saw 10 is preferably of as thin a gauge as may be employed to do its work of cutting, so as to effect the least waste of material in operation.

105 110 At right angles to the respective shafts 5 and 6 is provided a main drive shaft 12 car-

ried in suitable pillow blocks 13 and 14 provided for it on the table 1. The shaft 12 is provided with a drive pulley 15 and with driving means, for example a roller 16, fixed 5 to it between the pillow blocks 13 and 14. The roller is, in effect, a succession of pulleys, being divided for the accommodation of a plurality of any preferred number of conveyors, preferably endless flexible 10 conveyors into as many spaced grooves in its periphery as the number of the conveyors requires. Four conveyors 17, 18, 19 and 20, is the number shown in the drawings, and the number of grooves in the roller 16 cor- 15 responds therewith.

Above the plate 1, in parallel relationship to the shaft 12, I provide two shafts 21 and 22 carried in respective pillow blocks 23 and 24 secured to the top of the plate 1. The 20 shaft 22 carries a succession of grooved pulleys 26, 27, 28 and 29, that are in co-operative alignment with a corresponding succession of grooved pulleys 30, 31, 32, and 33, upon the shaft 21, and also with the 25 grooved pulley 16 or pulleys upon the shaft 12, as described. It is because the pulleys upon the shaft 12 may be of uniform diameter, unlike those upon the shafts 21 and 22, respectively, which are preferably of different 30 diameters, that I prefer to employ the grooved roller construction 16, as above described. If preferred, instead of the grooved roller 16, a succession of separate pulleys upon the shaft 12 may obviously be employed.

The flexible conveyors above indicated, besides passing around and in operative engagement with the pulleys upon the respective shafts 21, 22, and 12, preferably pass 40 around a series of pulleys 35, 36, 37, and 38, mounted, for example, upon a shaft 40 carried in hangers 41 and 42 secured to the bottom of the plate 1 as shown in Figures I and III. In reaching from the pulleys upon the 45 shaft 12 to those upon the shaft 40, and thence to those upon the shaft 21, the flexible conveyors aforementioned pass below the plate 1 through openings therein provided for their accommodation. The shaft 50 40 with its pulleys mounted below the plate 1 is provided as a means for adjusting the tension of the aforesaid conveyors, and to that end the hangers 41 and 42 may be made adjustable upon the plate 1, although adjustment of the pillow blocks 13 and 14 might 55 be provided to like effect.

The pulleys 35 to 38, inclusive, are also 60 designed and adapted to dispose of the sag of the flexible conveyors, which they carry, below the lower reach of the saw 10, as shown in Figures I and III, for example, so that the travel, respectively, of the conveyors and of the saw may be effected without interference of the one with the other.

65 The conveyors 17 to 20, inclusive, are rep-

resentative of any suitable feeding mechanism of any type preferred for conveying the material to be cut to the saw, and may be of any suitable and preferred type, such, for example, as flat sprocket-chain belts, 70 equipped, if preferred, with any suitable means for aiding their function, that being in respect to any conveying mechanism that may be used to feed material to be cut to the cutting stretch 11 of the band-saw 10, which 75 preferably has imparted to it, by aid of suitable means adapted to the purpose, a true horizontal disposition.

Heretofore in edging machines the cutting has been done by circular saw blades 80 whose necessary thickness has demanded an excessive width of kerf with consequent waste of the stock or material to be sawed. An additional objection to the use of circular saws in edging machines as heretofore 85 constructed, has been the necessity of adjustment of the saw to its work or of the work to its saw in order to effect a desired output. The result has been that, in such case, the personal equation of the operator 90 determines the output of the machine, and that it has been practically impossible to attempt accurate standardization of widths in edging material. By my invention both of the objectionable factors above referred 95 to are eliminated, and economical manufacture of the stock into desired widths is accomplished, partly by a large proportionate gain in the width of the kerf made by the saw, and also with substantially perfect 100 uniformity of width in the different sizes of stock cut by the machine.

In respect to means for effecting the end just referred to, it is now in order to specify that each of the endless flexible conveyors 105 17 to 20, inclusive, is designed and adapted to be driven in a true substantially horizontal plane between its respective pulleys upon the shafts 21 and 22, respectively. To that end, between its pair of pulleys each 110 conveyor travels upon and is supported by a floor 45 (compare Figures I and III) of a relatively narrow, elongated feed-box provided for it. Each feed-box comprises, besides the floor 45, opposite, parallel, vertical 115 side-walls 46 and 47. Each of the feed-boxes is accurately aligned with the endless conveyor to which it is appropriated, and the floor 45 thereof should be in substantially true tangential relationship to the 120 peripheries of the pulleys upon the shafts 21 and 22, respectively, about which said conveyor travels. The complementary pairs of pulleys upon the shafts 21 and 22, respectively, being of unequal diameters, the 125 endless conveyors accommodated thereon, respectively, occupy different horizontal planes according to the respective diameters of said pairs of pulleys, and as clearly indicated in Figure III of the drawings. With 130

this in mind, it will be obvious that if a board, or rectangular piece of lumber, of sufficient width be set edgewise upon any one of the endless conveyors 17-20, it will, 5 by the travel of said conveyor, be carried in the plane of the conveyor and fed to the saw 10. It will further appear that the vertical distance between the saw and each conveyor is constant, and that, therefore, 10 for each conveyor a uniform width of cut by the saw will be made. In Figure I, illustration is made in cross section of two boards 50 and 51 carried upon the conveyors 19 and 17, respectively, and as undergoing 15 the process of being severed into strips of different widths. From a study of that figure, it may be understood that a board may be passed successively through the machine upon the different conveyors, beginning with 20 the one whose floor 45 is farthest removed from the saw, and ending with the one that is nearest to it, and that in that manner the board may be ripped into graduated widths of strips.

25 Each of the feed-boxes is designed to be of a width to accommodate either an extreme width of board to be sawed, or, a plurality of thinner boards set side by side upon the conveyor. To this end one side 30 of each box is provided with a yielding support or supports, for example flat springs 52 and 53, that are adapted by their resiliency to press against the side of a board and hold it in true alignment with the side of the box 35 opposite to that which carries the springs.

The feed-boxes, as specified, are separated one from the other by ample clearance space for the stretch 11 of the saw 10, so that the saw may clean itself of sawdust between 40 each box. The width of the box is determinable by the width of cut which the saw may make without choking. It will also be apparent that all the feed-boxes may operate simultaneously or separately and that the 45 capacity of each box may be, if desired, adapted to accommodate at one time a number of boards set side by side in the box.

The stretch 11 of the saw is guided through the feed-boxes by a succession of 50 guide-jaws 55 and 56 which may be of any usual or preferred type, such as illustrated, for example, in Figure III, and of which as many as one pair for each box if preferred may be provided.

55 The feed-boxes, already described, terminate in close or operative proximity to the cutting edge of the saw, as shown in Figure III, for example. At a suitable short space behind the stretch 11 of the saw is provided 60 a succession of boxes 57, 58, 59, and 60 (compare Figures II and III). The boxes last named may be designated delivery-boxes as contradistinguished from the feed-boxes already described, with which, respectively, they are in accurate alignment. The

delivery-boxes afford means for carrying the ripped stock through the machine, and for discharging it by rotation of the respective pulleys upon the shaft 22.

In Figure IV, I illustrate in side elevation 70 a board 50, in its passage through a pair of feed and delivery boxes, showing the saw-stretch 11 at work to sever a gauged strip 61 from the board 50 by the cutting of a kerf 62.

75 For the sake of clearness, it is repeated that the drawings are in a measure diagrammatical. For that reason mechanical supporting elements for the feed and delivery boxes are not illustrated, but are, of course, assumed to exist.

80 The operation of my machine will be, in the main, understood from the foregoing specification, in view whereof it is deemed sufficient to add only the following by way 85 of brief description of the operation. Power being applied to the belt pulleys 7 and 15, respectively, motion is imparted to the saw 10, and to the several conveyors 17-20, in the direction of the arrows in Figure II. 90 Stock to be sawed is then supplied to one or more of the feed-boxes, as shown, for example, in Figure I. The operating machine continues to do its work so long as any of the boxes are kept supplied with stock, 95 which may be derived from a supply of new stock or from repeated sawings of material discharged from the delivery boxes until all of the stock is reduced to the minimum width the machine is adapted to cut. In 100 this connection it may be observed that by using a board 50, for example, of calculated maximum width, with allowance made for kerfage, the board may be ripped with substantial accuracy and without any unnecessary waste into strips of desired widths.

105 It is proper to add that, in order to accomplish my invention, conveyors, boxes, and driving mechanism, combined substantially as specified, may be used in connection with 110 any suitable or standard make of horizontal bandsaw.

What I claim is:

1. In a device of the class described, a band saw having a horizontal cutting run, a 115 plurality of substantially parallel spaced endless conveyors having a path of travel beneath and substantially at right angles to said band saw, a plurality of co-axial pulleys mounted on a common shaft on each side of said band saw and traversed by said conveyors, the pulleys on the same side of the saw being of different diameters and the aligned pulleys on opposite sides being of corresponding diameters, a plurality of elongated trough-like feed boxes on one side of said band saw through which said conveyors 120 pass, and a plurality of elongated trough-like receiving boxes on the other side of said band saws through which the conveyors 125 130

pass, the receiving boxes being in alignment with the feed boxes, said feed boxes being disposed in substantially tangential relation to the pulleys on the same side of the band saw and having their bottoms in distinct horizontal planes.

2. In a device of the class described, a band saw having a horizontal cutting run, a plurality of substantially parallel spaced 10 endless conveyors having a path of travel beneath and substantially at right angles to said band saw, a plurality of co-axial pulleys mounted on a common shaft on one side of said band saw and traversed by said conveyors, a corresponding number of co-axial pulleys on the opposite side of said band saw mounted on a common shaft and traversed by said conveyors, the pulleys on the same side of the saw being of different diameters and the aligned pulleys on 15 opposite sides being of corresponding diameters, a plurality of feed boxes on one side of said saw through which the conveyors pass, and a plurality of receiving boxes on the other side of the band saws through 20 which the conveyors pass, said conveyors having their runs beneath the saw in different horizontal planes.

25 3. In a device of the class described, a

band saw having a horizontal cutting run, a plurality of substantially parallel spaced 30 endless conveyors having a path of travel beneath and substantially at right angles to said band saw, a plurality of co-axial pulleys mounted on a common shaft on one side of said band saw and traversed by said conveyors, a corresponding number of co-axial pulleys on the opposite side of said band saw mounted on a common shaft and traversed by said conveyors, the pulleys on the same side of the saw being of different diameters and the aligned pulleys on 35 opposite sides being of corresponding diameters, a plurality of feed boxes on one side of said saw through which the conveyors pass, and a plurality of receiving boxes on the other side of the band saws through which the conveyors pass, said conveyors having their runs beneath the saw in different horizontal planes.

40 In testimony whereof, I have hereunto set 50 my hand in the presence of two subscribing witnesses.

ARNO MEREEN.

Witnesses:

JOSEPH L. ATKINS,
